UNITED STATES PATENT OFFICE.

FRANK L. BARNICK, OF NEW YORK, N. Y., ASSIGNOR TO CHARLES W. OSTERTAG, OF NEW YORK, N. Y.

HINGE.

SPECIFICATION forming part of Letters Patent No. 692,175, dated January 28, 1902.

Application filed May 1, 1901. Serial No. 58,337. (No model.)

To all whom it may concern:

Be it known that I, FRANK L. BARNICK, a citizen of the United States, residing at Manhattan borough, New York city, county and 5 State of New York, have invented new and useful Improvements in Hinges, of which the following is a specification.

This invention relates to what may properly be called a "roller hinge" or "roller spring-hinge," which can be made to allow considerable swing or movement of the door, as when the door is to open to a considerable extent or to swing to or close to the jamb.

This invention resides in the novel features 15 of construction set forth in the following specification and claims and illustrated in the annexed drawings, in which—

Figure 1 is a sectional view of the hinge applied to the door, the latter being closed. 20 Fig. 2 is a section along x x , Fig. 1. Fig. 3 is a section along y y , Fig. 1. Fig. 4 is a view like Fig. 3, the door being open. Fig. 5 shows a modification.

The door 1 is shown provided with a bridge 25 or door piece 2, adapted to engage a stem 14, so that as the door swings or opens and closes the bridge or connecting piece 2 oscillates the stem. The arms 17, projecting from or rotating with the stem, carry rollers or easters 30 4 and 4', made to travel on ridges or cam-surfaces 5 and 5'. Two sets or pairs of cams are shown, each pair extending from or forming part of a plate. These plates are indicated at 6 or 6' and are shown as movably seated 35 about the stem or one above the other.

A box 9 is shown with bottom 8 and cap 10, and the plates 6 6' have lugs or eyes for the passage or engagement of screws or fastenings 11. The cams or plates 6 6' being placed 40 in the box and the cap 10 put in place and the bolts or fastenings 11 being made to engage or be secured to the cap and bottom, said bolts will pass through or connect such cap and bottom with plates 6 6' and prevent the latter from turning, while the passages through 45 said plates are such as to permit of vertical movement on said bolts. The cam-plates are thus held from rotary movement and are separated by a series of springs, as at 12, while 50 the rollers 4 and 4' can travel back and forth

over the cam faces or surfaces 5 and 5'. As the door opens, the rollers mounting or running onto the high parts of the cams, the springs are compressed or the cams slid on stem 14, nearer to one another. This spring-pressure or tendency of the cams to separate 55 closes the door on the release of the latter, the cam-faces rising or separating as the rollers run from the high to the low cam portions.

The spring-pressure can be varied or regulated. For example, springs of greater or less tension can be selected, or the number of springs can be varied—say two springs for certain pressure and a greater number of springs when increased tension or spring is 60 called for—or a number of coiled springs can be placed concentrically or slipped one into the other, as the closed sections of a telescope, so as to secure appreciable stiffness at 65 each individual spring.

The bridge 2 is readily applied, or the door being suitably cut or recessed the bridge and door can be slid or seated one to the other, and the screws 15 connect or secure the parts. 70 At the front or outer end portion of the bridge 75 the seat or cut in the door can be somewhat widened or a slight degree of play allowed, so that the door can be brought to the required line or sit accurately in closing position when the rollers are at the bottom of the 80 cams. When closed, the door is held shut by the device against the wind or like accidental openings. The bridge and head 14' can also be pinned or secured together, a pin 85 being indicated at 15'.

The box-cap or its under face is shown with a stop 16, Fig. 1, projecting into the path of a roller or its arm 17, so as to limit the swing or opening of the door or prevent the rollers running off the end or top portions of the 90 cams. In other words, a roller starting from the bottom of a cam cannot swing clean around to the starting or bottom point; but having reached the crest of the cam such roller is arrested by stop 16 and has to retreat to return to the cam-bottom.

The cams 5 and 5' of each pair, it is noticed, are arranged concentrically or one within the other—that is to say, each roller while traveling on its own cam will not come into the cir- 100

cumference or boundary of the path or cam of the other roller of the pair. Say the two cams were of equal diameter or located on the circumference of one and the same circle. Then 5 each roller could not travel more than a half-circle without coming onto the cam or path of its companion roller. By the concentric arrangement shown, however, it has been found in practice that cams can be made, say, for 10 example, of two hundred and seventy degrees, or, in other words, a self-closing door can be arranged to swing through three-quarters of a circle instead of only a half-circle, or one hundred and eighty degrees.

15 The stems or bolts 11, besides holding the cams, also serve as guides on which the cams can slide toward or from one another. A finishing-cap is shown at 18, which can serve to give a finish or neat appearance, but also acts 20 as a sort of cover or protector for cap 10, to which the finishing-cap can be secured by suitable screws or fastenings. The cap 10 is also shown with a flange or rim about the hole or seat entered by stem 14, and the finishing-cap can be of such thickness as to bring its top face flush with the top of this rim, which latter acts as a sort of protector against water or foreign matter leaking or working into the box. The balls 7 and 7' at 25 the bottom of the stem 14 and at box-bottom 30 8 allow easy movement or swing of the door.

The box 9 is shown of angular or non-circular form, which insures against rotation of the box when the latter is fitted or sunk into 35 a corresponding seat in the floor or "saddle," as that part of the floor or sill receiving the box is sometimes called.

The stem 14 can be one cylindrical piece, to which the cams are pinned or secured; but 40 another practical construction, it has been found, is a stem composed of two parts 14^a, Fig. 5, between which the roller-arms 17 swing or are mounted.

No claim is made herein to what is shown 45 in United States Patent No. 607,728, granted July 19, 1898.

The cams 5 5' are shown with slight recesses or concavities, and the rollers 4 4', sitting into these seats or depressions when the 50 door is in closing position, hold the door firmly closed or act as a sort of antirattler to prevent the door being vibrated or shaken by the wind or other disturbances. The door is thus what might popularly be called "wind- 55 proof."

It should be noted that the cams are on different levels. The inner cam 5' being on a lower level than the outer cam, the arm of the roller running on such outer cam can 60 swing or travel over the top point or shoulder of the inner cam-circle when the door is swung open to a considerable extent.

What I claim as new, and desire to secure by Letters Patent, is—

65 1. A hinge comprising a bridge or door piece, rollers made to swing or travel with said bridge, means for suitably connecting

the rollers with the bridge or door piece, and means provided with cam faces or surfaces for the rollers placed out of the path of one 70 another to allow extended travel of the rollers substantially as described.

2. A hinge comprising a bridge or door piece, rollers made to travel with said bridge, means for connecting said rollers with the 75 bridge or door piece, and spring-actuated means provided with cam faces or surfaces on which the rollers travel, said cam faces or surfaces being arranged concentrically or one within the other substantially as described. 80

3. A hinge comprising a bridge or door piece, upper and lower spring-actuated cam faces or surfaces, means for suitably supporting said cam faces or surfaces, and rollers made to move with the door and to travel on 85 the respective cam faces or surfaces, and means for connecting the rollers with the bridge or door piece substantially as described.

4. A hinge comprising a door-piece, upper 90 and lower plates provided with cam faces or surfaces, a spring between the plates for separating the same and means for supporting said plates, a stem made to swing with the door and suitably connected with said door-piece, and rollers on the stem made to move with the door and to travel on the respective cam faces or surfaces substantially as described.

5. A hinge comprising a door-piece, upper 100 and lower cam-pieces and means for suitably supporting said cam-pieces, separating-springs for the cam-pieces, stems or bolts for securing the cam-pieces against rotation, a stem made to move with the door and suitably connected with said door-piece, and rollers connected to the last-named stem, said 105 rollers being made to travel on their respective cams and to clear the other cams substantially as described. 110

6. A hinge comprising a door-piece, rollers made to move with the door, and means for supporting said rollers suitably connected with the door-piece, a box having a bottom and cap, fastening-stems for engaging the 115 bottom and cap, spring-separated cam-pieces having eyes engaged by said stems, said rollers being made to travel respectively on the cams, and means for suitably supporting said cam-pieces substantially as described. 120

7. A hinge comprising a door-piece, a box having a cap, a pair of vertically-moving cam-pieces arranged in the said box, a spring interposed between the said cam-pieces and suitably connected thereto, a stem adapted to move with the door, connected with the door-piece and extending through the cams, arms projecting from the stem, a stop connected with the said cap, and rollers carried by the arms, adapted to travel along the 125 cams and engaged by said stop for arresting their movement.

8. A hinge comprising a door-piece, a box having a cap and a bottom, spring-separated

cams in the box, rollers made to travel on the cams, and a stem extended through the cams and to which the rollers are connected, said stem and box-bottom having coinciding ball-bearings for rotatively supporting the stem substantially as described.

9. A hinge comprising a bridge or door piece, a pair of vertically-moving cams, a spring interposed between the said cams and 10 suitably connected thereto, means for supporting the said cams, rollers connected with the door-piece and adapted to travel on the cams, and means for arresting the movement of the said rollers.

15 10. A hinge comprising a bridge or door piece secured to the door, a stem connected with said bridge or door piece, provided with rollers and rotated by the opening and closing of the door, spring-actuated vertically-moving cams for the rollers and provided 20 with seats or recesses into which the rollers enter for securing the door in closed position and a spring interposed between said cams

and suitably connected thereto substantially as described.

11. A hinge comprising a bridge or piece secured to the door, rollers connected to the bridge to swing with the door, oppositely-located vertically-moving cam pieces or disks, each having its cams provided with seats or 30 depressions into which said rollers enter to secure the door in closed position and means for causing the vertical movement of said cam-pieces substantially as described.

12. A hinge comprising a bridge or door 35 piece, rollers made to swing or travel with the door, and cams for the rollers placed out of the path of one another and on different levels substantially as described.

In testimony whereof I have hereunto set 40 my hand in the presence of two subscribing witnesses.

FRANK L. BARNICK.
